UNITED STATES PATENT OFFICE.

JAMES E. EDICK, WELLINGTON E. SMITH, AND SENECA P. RISLEY, OF BINGHAMTON, NEW YORK.

STAND FOR WASHTUBS.

No. 831,268.

Specification of Letters Patent.

Patented Sept. 18, 1906.

Application filed October 5, 1904. Serial No. 227,317.

To all whom it may concern:

Be it known that we, JAMES E. EDICK, WELLINGTON E. SMITH, and SENECA P. RISLEY, citizens of the United States, residing at 5 Binghamton, New York, have invented certain new and useful Improvements in Stands for Washtubs, of which the following is a specification.

Our invention relates to stands for wash-tubs and the like, and has for its object to provide a bench or stand of this kind that may be folded in such a manner as to occupy a very small space and which will also be strong and durable and not liable to collapse 15 under the weight of the tub.

With these objects in view our invention consists of the construction hereinafter described, and more particularly pointed out in the claims.

20 Referring to the drawings, Figure 1 is a perspective view showing the stand in its extended position. Fig. 2 is a similar view showing the stand folded. Fig. 3 is a top plan view of the stand in its extended position. Fig. 4 is a section on line 4 4 of Fig. 2.

In carrying out our invention we employ four upright standards A of sufficient strength to support the weight of the tub when filled. Firmly secured to the standards A, near the 30 extremities thereof, and extending at right angles thereto, are the arms B B', which extend inwardly toward a common center and are there joined by the plate C. This plate is of metal and is preferably square and is provided at each side with two bolts c c', the bolts c being in diagonally opposite corners of the plate C, as are the bolts c'. These bolts pass through the inner ends of the arms B B and B' B', joining the same, and 40 thereby forming two practically continuous cross-bars. The arms B are rigidly secured at their ends to the diagonally opposite corners of the plate C by means of the bolts c, forming a substantially continuous connection 45 between the standards. The arms B' have their free ends rounded and loosely se-

cured to the remaining diagonally opposite corners of the plate C by means of the bolts c', which are provided with thumb or wing nuts, whereby the bolts may be loosened to 50 allow the arms B' to be swung out at an angle to the arms B and then tightened to lock the arms B' in their extended position.

In order to make the stand capable of supporting tubs at different heights, the upper 55 and lower sets of arms B B' are secured to the standards A at different distances from the extremities thereof, and as the tub rests upon these arms it will be seen that by reversing the stand the tub will be supported 60 at different levels.

We do not wish to be limited to the exact structure herein described, as it will be apparent that the shape of the plate C and the nature of the fastening devices c c' may be 65 varied without departing from the spirit of our invention.

Having described our invention, what we claim is—

1. A device of the class described comprising the standards, arms secured to said standards, a plate having a corner on each of said arms, means for rigidly securing two of said arms to diagonally opposite corners of said plate and means for adjustably securing two 75 of said arms to the remaining corners of said plate, substantially as described.

2. A stand of the class described comprising the standards, the arms, the plate having a corner resting on each of said arms, bolts 80 extending through said plate and said arms and thumb-nuts on two of said bolts in diagonally opposite corners of said plate, substantially as described.

In testimony whereof we affix our signatures in presence of two witnesses.

JAMES E. EDICK.

WELLINGTON E. SMITH.

SENECA P. RISLEY.
